UNITED STATES PATENT OFFICE

141,635

DESIGN FOR AN EJECTOR FORK

Edith Fromm, New York, N. Y., now by certificate
of court Edith Neuhaus

Application December 16, 1944, Serial No. 116,936

Term of patent 14 years

(Cl. D44—29)

To all whom it may concern:

Be it known that I, Edith Fromm, a citizen of the United States of America and residing in the city, county, and State of New York, have invented a new, original, and ornamental Design for an Ejector Fork, of which the following is a specification, reference being made to the accompanying drawing, forming a part thereof.

Fig. 1 is a front elevational view of the ejector fork showing my new design.

Fig. 2 is a side elevational view of the fork shown in Fig. 1.

Fig. 3 is a rear view of the fork shown in Fig. 1 with the ejector in extended position and with the handle of the fork broken away.

The dominant features of my design reside in the portions shown in full lines.

I claim:

The ornamental design for an ejector fork, substantially as shown and described.

EDITH FROMM.
